UNITED STATES PATENT OFFICE

MINOR F. H. GOUVERNEUR, OF BALTIMORE, MARYLAND, ASSIGNOR TO LOCKE INSULATOR CORPORATION, OF BALTIMORE, MARYLAND, A CORPORATION OF MARYLAND

INSULATOR CUTTER AND METHOD OF TREATING INSULATORS

Application filed January 7, 1927. Serial No. 159,630.

The invention relates to devices for working upon insulators, particularly those of the Hewlett type and has for its principal object the provision of a device for scooping out 5 or cutting a small portion of the porcelain at the places where it is intended to cut the curved passages provided for the reception of suspension links.

It is well known that insulators of the 10 Hewlett type consist of dielectric bodies having curved interlinking passages therein for the reception of suspension links which are adapted to be connected in series with corresponding links of an adjacent unit for forming 15 a string or chain. The passages must be formed in the insulator unit while it is in a plastic or green state and the passages themselves may be formed in various ways as for instance as disclosed in my Patent No. 1,413, 20 023 dated April 18th, 1922, or No. 1,697,422 dated January 1, 1929, or No. 1,697,423 dated January 1, 1929, or by a mechanical device such as that forming the subject matter of 25 Patents Nos. 1,697,434 or 1,697,435 granted January 1, 1929 to Stewart L. Moore. As a 30 matter of fact, it is immaterial to the present invention how the curved passages themselves are cut. Suffice it to say that when a cutting machine is used, when the cutters engage the insulator the clay is crowded and caused to bulge upwardly beyond the top surface of the insulator. Naturally, this result is objectionable as subsequent trimming by hand work is required.

35 It is with the above facts in view that I have designed the present invention which has for an important object the provision of a simple device by means of which the top of the insulator may be scooped out at the areas 40 where the ends of cutting tools, such as disclosed by Moore, will enter the clay, or at the areas where a tool such as those disclosed in my above mentioned patent and co-pending applications will enter and emerge, the scooping 45 away of the material at these points compensating for the upward crowding or bulging so that notwithstanding such a condition the material will not project above the surface of the major portion of the top of the 50 insulator.

Another object of the invention is to provide a method of treating an insulator of the Hewlett type preparatory or preliminary to the cutting of curved interlinking passages therein so that the bulge resulting from 55 crowding out of the material by the passage of a cutter therethrough will not project beyond the surface.

Another object of the invention is to provide a device for this purpose so constructed 60 and arranged that it may be simply set upon the insulator to be cut without it being necessary to employ any elaborate frame or holding means, the device being so arranged as to be self-centering when placed upon the top 65 of the insulator.

Another object of the invention is to provide a cutter of this character embodying a relatively stationary supporting structure 70 and a relatively movable knife or cutter detachably mounted and of such form that when operated it will produce a substantially spoon shaped concavity.

A further object of the invention is to provide cutting means of this character which can also be used, if desired, for similarly cutting the underside of the insulator, of course in inverted position, at points 90° from the corresponding points or areas at the top surface, it being, however, conceivable that the 75 concavities at the underside may be readily formed by employing projections in the bottom of the mold in which the insulator is initially shaped so that the scooping will be 80 required only at the top surface.

Still another object of the invention is to provide a cutter of this character which may be constructed to scoop the top of the insulator at one side, subsequently to which it should be shifted to effect scooping at the 85 opposite side of the center, or which may be provided with duplicate cutting elements so that both scoops may be made without shifting the position of the supporting member.

An additional object is to provide a device of this character which will be simple and inexpensive to manufacture, easy and convenient to use, positive in action, efficient and durable in service, and a general improvement in the art.

With the above and other objects and advantages in view, the invention preferably consists in the arrangement and combination of parts and detailed structural features to be hereinafter more fully described and claimed, and illustrated in the accompanying drawings in which:

Figure 1 is a cross sectional view through an insulator showing the device in position upon the top thereof with the cutting tool at practically the beginning of its stroke, the curved passage to be subsequently cut being illustrated by dot and dash lines and the remainder of the path of the movable cutter being illustrated by heavy dotted lines,

Figure 2 is a fragmentary plan view with the cutting tool removed,

Figure 3 is a fragmentary edge elevation of the supporting portion of the device with the tool removed,

Figure 4 is a detail elevation of the tool alone, and

Figure 5 is a fragmentary section showing a means for forming the concavities in the undersurface.

Referring more particularly to the drawings, the numeral 1 designates an insulator unit of the Hewlett type within which are to be cut curved interlinking passages for the reception of the usual suspension links, not shown. The passages to be cut are indicated at 2 and 3 by dot and dash lines. The passage 2 is of course to be cut from the top of the insulator whereas the passage 3 is formed from the underside thereof. The exact cross sectional shape of the insulator may of course be varied and that disclosed in the drawings is simply for purposes of illustration.

In carrying out the invention, use is made of a suitable supporting block 4 which may of course be the mold within which the insulator itself is formed and this block has a curved upper surface 5 conformingly engaging against the undersurface of the insulator. It should be understood that this block need not be the mold as it can be a separate element entirely upon which the green insulator is set, there being no restrictions in this respect, the only requisite being that some adequate means be provided for supporting the insulator and preventing it from becoming distorted while worked upon by the cutter. In some varieties of insulators of this type there is provided a channel or groove 6 spaced slightly inwardly from the edge and I preferably take advantage of this fact by providing a supporting ring 7 or the like so shaped as to fit substantially within this groove. The engagement of this ring member within the groove or channel will act to center the ring without the employment of any auxiliary or extraneous means for the purpose though of course any equivalent means may be provided for retaining this supporting ring at the desired location

with respect to the insulator. Mounted upon the supporting ring member 7 is a fulcrum structure here shown as including a pair of spaced uprights 8 upon which is pivoted the cutter 9 which may consist of a handle 10 carrying a blade 11 which is conveniently a simple strip of thin metal bent into substantially U-shape with its arms suitably secured to the handle. The handle carries oppositely extending trunnions 12 which might of course be permanently pivotally connected with or mounted upon the upright supports or brackets 8 but which are preferably engaged within notches 13 therein so that the cutter itself may be detached readily in case the occasion should arise. Obviously, one pair of uprights only may be provided if preferred though it is probably better that two sets be used located at diametrically opposite points on the supporting ring member 7 as disclosed in Figure 1, the cutter 9 being engageable upon either set or pair.

In the operation, let it be assumed that the insulator is resting upon the supporting member 4 or in a mold as the case may be. The operator lays the ring member 7 upon the top of the insulator, engages the trunnions 12 of the cutter within the notches 13 of the pair of uprights with the cutter in such position that the blade 11 is above the insulator, and then swings the cutter downwardly as illustrated by the arrow in Figure 4. The blade 11 will then engage the insulator and scoop out a portion of the material, the path of movement of the blade being indicated by the heavy dotted line 14. In order that the blade may pass clear through the material of the insulator at the inner periphery of the ring without interference, it is preferable that the ring be notched at 15 as illustrated most clearly in Figure 2. The shape and length of the cutter and the relation thereof to the supporting ring are such that this scooped out concavity will be at that area of the insulator at one end of the curved passage 2. If the member 7 is provided with two sets of upright brackets, the cutter may then be removed from the set upon which it was initially engaged and then engaged upon the other set or pair so that a second cut may be made at the opposite side of the center of the insulator where the other end of the curved passage 2 will be. Of course, if there is only one set of supporting brackets the entire ring member must be shifted so as to bring the brackets at such a position that the second made cut will be diametrically opposite the first.

If desired, the insulator may be turned over and the other side treated in the same manner, it being clear that the entire device would then need to be operated in a position at 90° from that in which it was placed when operating on the top of the insulator for the reason that the ends of the curved passages

are arranged 90° apart. However, it is readily conceivable that concavities may be formed in the underside of the insulator at the proper points simply by providing projections 16 in the mold. After the top and bottom of the insulator have been formed with the concavities, it is ready to have the curved passages 2 and 3 cut by any of the methods or devices above referred to and in actual 10 practice I have discovered that the scooped out places or concavities will permit the crowding or bulging of the clay at the ends of the passages without the material being forced up beyond the top surface of the insulator. Any subsequent trimming is thus 15 rendered unnecessary.

If it should be so desired, it is apparent that the device can be used in a different manner. It is clear that the curved interlinking 20 passages might be formed first, subsequently to which my cutting mechanism may be employed for removing any material crowded or bulged upwardly by the passage of the cutting tools through the clay. While this is 25 not the preferred method it is mentioned as a possibility.

From the foregoing description and a study 30 of the drawings it will be apparent that I have thus provided a simply constructed, inexpensive and easily applied and used tool for the purpose specified and one which will effect a considerable saving in time and labor. It is believed that the construction, operation and advantages will be readily apparent 35 to one skilled in the art without further explanation.

While I have shown and described the preferred embodiment of the invention, it should be understood that the disclosure is merely 40 an exemplification of the principles involved as the right is reserved to make all such changes in the details of construction as will widen the field of utility and increase the adaptability of the device provided such 45 changes constitute no departure from the spirit of the invention or the scope of the claims hereunto appended.

Having thus described the invention, I claim:

50 1. A device of the character described comprising a supporting member adapted to be mounted upon the top of an insulator, bracket members on said support, and a cutter pivotally mounted on said bracket members and having a substantially U-shaped blade adapted to cut through the material of the insulator along an arcuate path for scooping out the material at one side at a relatively small area.

60 2. A device of the character described comprising a supporting ring member adapted to be engaged upon the top of an insulator of the Hewlett type, a pair of supporting brackets on said ring member, and a cutter detachably pivotally engaged upon the brack-

ets and having a curved blade movable in an arcuate path for scooping out a shallow concavity at the top of the insulator.

3. A device of the character described comprising a ring member adapted to be engaged upon the top of an insulator of the Hewlett type, pairs of fulcrum brackets mounted on said ring member at diametrically opposite points, and a cutter detachably pivotally engageable upon a selected 70 pair of brackets and having a curved blade movable in an arcuate path intersecting the surface of the insulator for scooping out a portion of the material thereof.

4. A device of the character described comprising a ring member adapted to be engaged upon the top of an insulator of the Hewlett type, pairs of fulcrum brackets mounted on said ring member at diametrically opposite points, and a cutter detachably pivotally engageable upon a selected pair of brackets and having a curved blade movable in an arcuate path intersecting the surface of the insulator for scooping out a portion of the material 80 thereof, the supporting brackets having notches therein and the cutter having trunnions engageable within said notches.

5. The method of making an insulator of the Hewlett type, comprising scooping out a portion of the material of the insulator at 95 one side thereof, and forming curved interlinking passages through the material with the ends of the passages at said scooped-out areas.

6. The method of treating an insulator of the Hewlett type comprising forming curved interlinking passages therethrough and scooping out a portion of the material of the insulator at the ends of the passages.

7. The method of treating an insulator of the Hewlett type comprising forming curved interlinking passages therethrough and scooping out a portion of the material of the insulator at the ends of the passages before or after the formation of the passages.

8. The method of making an insulator of the Hewlett type to be provided with interlinking curved passages opening out at opposite sides, comprising molding the insulator with depressions in one side at the areas 115 where the ends of one passage are to be located, and scooping out a portion of the material on the surface at the opposite side at the areas where the ends of the other passage are to be located.

In testimony whereof I affix my signature.
MINOR F. H. GOUVERNEUR.
